UNITED STATES PATENT OFFICE.

EDWARD C. MEIER, OF PHOENIXVILLE, PENNSYLVANIA; CHARLOTTA I. MEIER,
ADMINISTRATRIX OF SAID EDWARD C. MEIER, DECEASED, ASSIGNOR TO
HEINE SAFETY BOILER COMPANY, OF PHOENIXVILLE, PENNSYLVANIA, A
CORPORATION OF MISSOURI.

HEADER CONSTRUCTION FOR BOILERS.

1,304,500.

Specification of Letters Patent. Patented May 20, 1919.

Application filed July 9, 1917. Serial No. 179,536.

To all whom it may concern:

Be it known that I, EDWARD C. MEIER, a citizen of the United States, residing at Phoenixville, in the county of Chester and

5 State of Pennsylvania, have invented certain new and useful Improvements in Header Construction for Boilers, of which the following is a specification.

One object of my invention is to cheapen 10 and facilitate the construction of boiler headers.

Another object is to so construct my improved header that it can be easily secured to the boiler setting.

15 A further object is to make a header in such manner that the main portions can be cut in any desired lengths from rolled or pressed sheet metal and joined together, and independent heads can be forced within opposite ends of the joined main portions.

These objects, and other advantageous ends which will be described hereinafter, I attain in the following manner, reference being had to the accompanying drawings in 25 which

Figure 1 is an end elevation of a water tube boiler having headers constructed in accordance with my invention.

Fig. 2 is a sectional elevation taken on 30 the line 2—2 of Fig. 1.

Figs. 3 and 4 are perspective views of two main sections of my improved header.

Fig. 5 is a perspective of one of the independent heads.

35 Fig. 6 is an enlarged fragmentary view of the upper portion of the front header illustrated in Fig. 2.

Referring to the drawings, 1 and 2 are the front and rear headers which are 40 joined together by water tubes 3. Baffles 4 and 5 are secured to certain of the water tubes 3 as clearly shown in Fig. 2 so that the products of combustion arising from the fire box 6 will be compelled to heat the 45 water tubes 3 throughout their entire lengths.

The front header 1 includes two main sections 7 and 8. These sections are made of sheet metal which are rolled or pressed 50 into the shape shown in Figs. 3 and 4 and are each substantially channel shape in cross section and have longitudinally extending top and bottom flanges. Each of these sec-

tions is devoid of any flanges at the opposite ends, and therefore they can be made of 55 any length simply by cutting the required length from a long sheet.

The two inwardly turned flanges 9 and 10 of the section 7 are preferably scarfed at their extreme edges as shown at 11. The 60 flanges 12 and 13 of the section 8 are designed to overlap the flanges 9 and 10 as illustrated in Figs. 1, 2, and 6. The sections 7 and 8 with their respective flanges lapping each other as above described, are 65 joined together by rows of rivets 14 at the top and bottom.

Independent heads 15 are preferably stamped out of sheet metal and each of these heads 15 has a continuous inwardly extending flange 16 as clearly shown in Figs. 2, 5, and 6. These heads are forced within the opposite ends of the headers to close the end space between the sections 7 and 8.

The flanges 16 of the heads 15 engage the 75 inner surfaces of the sections 7 and 8 and are riveted thereto by rows of rivets 17. These heads are preferably forced within the headers under great pressure so as to completely form a seal and correspond to 80 the inner contour of the sections 7 and 8. The headers 1 and 2 are tilted as clearly shown in Fig. 2 so that the water tubes 3 connecting them, incline horizontally.

It will be noted that the rear section 8 of 85 the header 1 has a substantially flat portion 18 forming a part of its top flanges and this flat portion intersects the flat rear portion 19 at an incline, or in other words at an angle other than ninety degrees. The flat 90 portion 18 therefore does not extend parallel to the bottom lapped flanges 10 and 11.

Since the front header 1 tilts forwardly, I utilize the flat portion 18 to provide the 95 holes for connecting pipes or nipples 20 which lead to the steam and water drum 21. The nipples 20 extend substantially at right angles from the flat portion 18 and radially intersect the drum 21. This permits me to place the drum 21 in such position as not 100 to greatly overhang the supporting structure as will hereinafter be more fully described.

The drum 21 connects with the rear header in the present instance by tubes 22, the tubes 105 entering substantially flat portions 23 of the

forward section 24 of the header 2 as clearly shown in Fig. 2. In all other respects the header 2 is of the same construction as the header 1 above described and includes 5 a rear section 25 and end closing heads 26 which are similar to the heads 15 above described and connected to the sections 24 and 25 in the same manner as the heads 15 are connected to the sections 7 and 8 of 10 the header 1.

By constructing the headers as above described, the outer end surfaces of the heads 15 and 26 can be made substantially flat and thus provide ample securing space for 15 connecting plates 27. These connecting plates 27 are preferably riveted to the opposite heads of each header and in turn are riveted to uprights or columns 28 which form the main supporting means for the 20 boiler. Thus, the headers 1 and 2 are supported by the columns 28 through the medium of the plates 27, the connecting means between the plates 27 and the heads being 25 independent of the means which secure the several parts of the headers together.

The front columns 28 therefore can be placed in position to be directly under the axis of the drum 21, thus the front columns directly support the weight of the drum 21 30 and the front header 1. This relieves any strain on the nipples 20 and furthermore the construction of the header permits the drum to be set so as not to overhang the main supporting structure to any great extent. This is considered a point of material 35 advantage, since in boilers of this type constructed prior to my invention the connecting nipples from the headers have usually been taken straight out of the tops of the 40 tilted headers, and since the nipples intersected the drum radially, a great portion of the drum overhung the boiler setting. This required an extra amount of room to place the boiler and also required additional support for the extreme forward portion of the 45 drum.

By constructing a header in the above mentioned manner, headers of various lengths can be easily and quickly made up 50 by cutting the desired length of the main sections, joining them together, and afterward forcing in the end heads, thus no special dies are necessary as has heretofore been the custom where the ends as well as 55 the tops and bottoms of the headers were flanged.

I have illustrated in Figs. 1, 2, and 6, hand holes 29 which can be normally closed by hand hole plates 30, however, these hand 60 holes and hand hole plates can be of any desired construction and permit access to the interior of the headers and also to clean the tubes 3.

While I have described my invention as 65 taking a particular form, it will be under-

stood that the various parts of my invention may be changed without departing from the spirit thereof, and hence I do not limit myself to the precise construction set forth, but consider that I am at liberty to make such 70 changes and alterations as fairly come within the scope of the appended claims.

Having thus described my invention, what I claim as new and desire to secure by Letters Patent is:

1. A substantially rectangular box header for water tube steam boilers of the character described, including two sections cut from continuous lengths of sheet metal which has top and bottom flanges abruptly 80 bent in opposite directions substantially at right angles to the main portions of said sections and secured together, said main portions of one of the sections having a plurality of tube holes extending therethrough; 85 and independent heads secured to the ends of said main sections, substantially as described.

2. A boiler structure including a box header, having two main sections cut from 90 continuous lengths of sheet metal which has top and bottom flanges, said sections having their top and bottom flanges respectively overlapped and secured to each other, independent heads secured to and adapted to 95 close the ends of said main sections, one of said sections having a substantially flat portion included in its flange and bent at an angle other than ninety degrees (90°) to the rear and top surfaces of said section, a cross 100 drum extending above the header, and nipples connecting the drum with the header and passing through said substantially flat portion of the header section, substantially as described.

3. A boiler structure including two columns spaced apart and a tilting box header located therebetween, said header including two main front and rear channel sections each having top and bottom flanges 110 extending from end to end, said flanges overlapping and secured to each other, independent heads having inturned flanges forced between and secured in contact with the inner surfaces of the opposite end portions of 115 said main sections thus providing outer side surfaces for the heads free of obstruction, and plates connected to said latter surface and to the adjacent columns, substantially as described.

4. A boiler structure including two columns spaced apart and a tilting box header located therebetween, said header including two main front and rear channel sections each having top and bottom flanges 120 extending from end to end, said flanges being respectively overlapped and secured to each other, independent heads having inturned flanges forced between and secured in contact with the inner surfaces of the op- 130

posite end portions of said main section, thus providing outer side surfaces for the heads free of obstruction, nipples extending through the top flanges of one of said sections, a cross drum into which the upper ends of said nipples extend, said drum being supported by the tops of said columns, whereby the nipples are relieved of the strain of supporting the drum, and steam-generating means communicating with the interior of said header and with said drum, and

means secured to said outer side surfaces of the heads and directly to the columns, substantially as described.

In testimony whereof I have signed my ¹⁵ name to this specification in the presence of two subscribing witnesses.

EDWARD C. MEIER.
